FERDINAND STERN, OF BADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND.

OIL CIRCUIT BREAKER.

Application filed September 2, 1926, Serial No. 133,117, and in Germany October 5, 1925.

This invention relates to the construction of circuit breakers, of the oil quenched type, for high tension service.

A general object of the invention is the provision of improved construction for such devices which will afford increased insulating strength between the contacts or poles across which the circuit is opened.

An ancillary object is the provision of a construction which will likewise afford increased insulating strength between the contacts and the walls of the tank and other metallic portions of the apparatus.

A further object is the provision of a construction which will effect conservation of space and material in the construction of such devices, without sacrifice of insulating effectiveness.

Other and further objects of the invention will be pointed out or indicated hereinafter or will be apparent to one skilled in the art upon an understanding of the invention or its employment in practice.

In the accompanying drawing forming a part of this specification, I illustrate in diagrammatic fashion one arrangement for embodiment of the invention but it is to be understood that this is presented for illustration only and is not to be accorded any interpretation having the effect of limiting the claims short of the true and most comprehensive scope of the invention in the art.

In the drawing,

Fig. 1 is a cross sectional view, diagrammatic in nature, of a two pole oil circuit breaker, showing in a general way the tension fields about the poles or conductors carrying current in opposite directions, the section being taken on the line 1—1 in Fig. 2; and

Fig. 2 is a part sectional elevation, diagrammatic in nature, of such a device containing the invention, the section being taken on the line 2—2 in Fig. 1.

In oil immersed circuit breakers for the handling of high tension current, it is customary to provide mechanically operated means for opening and closing the circuit under oil, across fixed terminals or contact members. Necessarily, a proper strength of insulation must be maintained between these poles in order to prevent flashing over or the establishment of an arc when the circuit

breaker is either open or closed or in the process of opening. Various arrangements have been resorted to for strengthening the insulation afforded by the oil and the spacing of the terminals. The present invention provides an effective construction for this purpose. In the arrangement shown diagrammatically in the drawing, the reference numeral 10 designates the tank of the circuit breaker in which extend conductors 11 terminating in contacts 12, one of said conductors 11 being the in-leading line and the other being the out-leading line. Movable contacts 14 are carried by and conductively connected through a yoke 15, which is carried on vertically movable links 16 so that the contacts 14 may be moved downwardly away from contacts 12 to open the circuit. The tank 10 is filled with oil to a proper level submerging the contacts. Disposed in positions encompassing the contacts are cylinders 17 of insulating material, same being slotted at their lower portions, where necessary to accommodate the vertical movement of the yoke 15. The cylinders 17 are disposed in eccentric relationship so that their positions correspond generally to the equipotential zones of the tension field surrounding the contacts 12 and conductors 11. In Fig. 1 the dotted lines indicate generally the lines of force of the electrostatic field, and the dash line circles are to indicate generally areas of equipotential. With the respective cylinders 17 thus located approximately in equipotential areas, they are not subjected to extreme differences in potential between different points on their surfaces, and thus do not present creepage surfaces conducive to discharges which may result in flash-overs, as by this arrangement the electrical strain will be everywhere approximately at right angles to the insulating material.

A further important result accrues from this eccentric arrangement of the insulating cylinders, in that it makes for conservation of space without decrease of insulating strength. For high tension and extra high tension circuit breakers this is of great economical importance, as it avoids the necessity for extremely wide spacing of the terminals, and thereby avoids necessity for extremely large tanks and the requisite large quantity of oil necessary to fill them.

What I claim is:

1. In a circuit breaker, the combination with a tank and series switch contacts therein, of insulating shields encompassing the contacts in eccentric relationship with respect thereto, and oil submerging the contacts and shields.
2. In a circuit breaker, the combination with the circuit breaker tank and a plurality of sets of series-opening switch contacts therein, of insulating shields encompassing such sets of contacts and lying respectively in areas about such sets of substantially equipotential, and oil submerging the contacts and shields.
3. In a circuit breaker, the combination of a tank, oil therein, stationary contacts in the tank, connected movable contacts for connecting the stationary contacts, and insulating shields encompassing the contacts in eccentric relationship with respect thereto.
4. In a circuit breaker, the combination of a tank, oil therein, stationary contacts in the tank, movable contacts for closing on the stationary contacts, an operating member between the movable contacts, and insulating shields encompassing the contacts, the shields associated with respective stationary con-

tacts being arranged in eccentric relationship with respect thereto.

5. In a circuit breaker, in combination, a tank, line terminals therein, movable contacts for connecting said terminals in series, means connected between the movable contacts for operating them, and insulating shields encompassing respective terminals in eccentric relationship with respect thereto.

6. In a circuit breaker, in combination, a tank, an in-leading terminal and an out-leading terminal therein, a switch device for connecting said terminals, an operating member for said switch device, insulating shields encompassing the terminals, the shields associated with respective terminals being arranged in eccentric relationship with respect thereto, and oil immersing the shields and switch device.

7. In circuit-breaking apparatus, contact elements, and insulating members disposed about said elements in eccentric relation with respect thereto and with respect to each other.

In testimony whereof I have hereunto subscribed my name at Zurich, Switzerland, on the 13 day of August, A. D. 1926.

FERDINAND STERN.
